CLAIM

The ornamental design for a bag, as shown and described.

DESCRIPTION

FIG. 1 is a perspective view of a bag.

FIG. 2 is a front view thereof.

FIG. 3 is a rear view thereof.

FIG. 4 is a right-side view thereof.

FIG. 5 is a left-side view thereof.

FIG. 6 is a top view thereof.

FIG. 7 is a bottom view thereof; and,

FIG. 8 is a perspective view of the bag with one or more duplicate bags nested therein.

The broken lines in FIG. 8 illustrating duplicate bags depict environmental subject matter that forms no part of the claimed design. The remaining broken lines depict portions of the bag that form no part of the claimed design.

1 Claim, 6 Drawing Sheets
